(57) **ABSTRACT**

A new *Petunia* plant named 'PEHY0017' particularly distinguished by its mounding plant habit, medium sized, blue colored flowers with a pattern of dark blue veining, medium green foliage, good branching and early flowering.

1 Drawing Sheet

1

Latin name of the genus and species of the plant claimed:
Petunia hybrida.
Varietal denomination: 'PEHY0017'.

BACKGROUND OF THE NEW PLANT

The present invention comprises a new *Petunia*, botanically known as *Petunia hybrida*, and hereinafter referred to by the variety name 'PEHY0017'.

'PEHY0017' is a product of a planned breeding program. The new cultivar has a mounding plant habit, medium sized, blue colored flowers with a pattern of dark blue veining, medium green foliage, good branching and early flowering.

'PEHY0017' originated from a hybridization made in October 2010 in a controlled breeding environment in Enkhuizen, The Netherlands. The female parent was the unpatented proprietary plant designated 'P0192' with variable flower color, from light blue to blue depending on age, poor branching, and a very early flowering response.

The male parent of 'PEHY0017' was an unpatented proprietary plant identified as 'N0539-2' with a more semi-trailing habit, more vigour, late flowering and deep blue flower color.

The resulting seeds were sown in January 2011. 'PEHY0017' was selected as one flowering plant within the progeny of the stated cross in May 2011 in a controlled environment in Enkhuizen, The Netherlands.

The first act of asexual reproduction of 'PEHY0017' was accomplished when vegetative cuttings were propagated from the initial selection in June 2016 in a controlled environment in Enkhuizen, The Netherlands.

BRIEF SUMMARY OF INVENTION

Horticultural examination of plants grown from cuttings of the plant initiated in June 2011, and continuing thereafter, has demonstrated that the combination of characteristics as

2

herein disclosed for 'PEHY0017' are firmly fixed and are retained through successive generations of asexual reproduction.

'PEHY0017' has not been observed under all possible environmental conditions. The phenotype may vary significantly with variations in environment such as temperature, light intensity, and day length.

A Plant Breeder's Right for this cultivar was applied for in the European Union on Sep. 2, 2015 and assigned No. 2015/2039. 'PEHY0017' has not been made publicly available prior to the effective filing date of this application, notwithstanding any disclosure that may have been made less than one year prior to the effective filing date of this application by the inventor or another who obtained 'PEHY0017' directly from the inventor.

The following traits have been repeatedly observed and are determined to be basic characteristics of the new variety. The combination of these characteristics distinguishes this *Petunia* as a new and distinct variety.

BRIEF DESCRIPTION OF THE PHOTOGRAPHS

25 The accompanying photographic drawings show typical flower and foliage characteristics of 'PEHY0017' with colors being as true as possible with an illustration of this type.

The photographic drawings show in FIG. 1. a flowering plant of the new variety and in FIG. 2. a close-up of the flowers.

DETAILED BOTANICAL DESCRIPTION

35 The aforementioned photographs were taken in July 2015 from plants growing in a field trial in Enkhuizen, The Netherlands. These plants were approximately 17 weeks of age.

US PP28,240 P3

5

Quantity per flower.—5.

Color of filaments.—RHS 144D at base to RHS 83D
near anther.

Length filaments.—1.4-1.7 cm.

Anther color.—RHS 202C to RHS 84D.

Anther length.—0.05 cm.

Anther shape.—Rounded.

Color of pollen.—RHS 202C.

Pollen amount.—Moderate.

6

Fertility/seed set.—Has not been observed on this
hybrid.

Disease/pest resistance.—Has not been observed on
this hybrid.

5 What is claimed is:

1. A new and distinct variety of *Petunia* plant named
'PEHY0017' substantially as illustrated and described
herein.
